PARACHUTE FLARE

Sargent P. Huff, Chevy Chase, Md.

Application February 25, 1938, Serial No. 192,625

4 Claims. (Cl. 102—24)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a parachute flare. Parachute flares having a high candle power are dropped from aircraft for the purpose of illuminating the terrain to discover, for example, an emergency landing field or hostile troop movements and positions. The light rays from the burning flare interfere with observation from the aircraft and also disclose the position of the aircraft and expose it to hostile fire.

10 The purpose of this invention is to provide a flare with a shade which is released from folded position when the flare composition is ignited and which serves to intercept upwardly directed rays of light.

15 To these and other ends, the invention consists in the construction, arrangement and combination of elements described hereinafter and pointed out in the claims forming a part of this specification.

20 A practical embodiment of the invention is illustrated in the accompanying drawing, wherein:

25 Fig. 1 is a view in side elevation of a portion of a flare constructed in accordance with the invention and showing the shade in the open position.

30 Fig. 2 is a view in side elevation with parts in section and showing the shade in folded position.

Fig. 3 is a sectional view on the line 3—3 of Fig. 2.

35 Fig. 4 is a sectional view on the line 4—4 of Fig. 3.

40 Referring to the drawing by characters of reference there is shown the light case 5 of a flare which is adapted to be suspended by a cord 6 from a parachute, not shown. The light case contains a composition 7 which burns with great brilliancy to illuminate a considerable area. The composition 7 is ignited by means of a charge 8 of black powder which is placed in the lower end 45 of the case and which is ignited in the usual manner from a quickmatch 9 during the descent of the flare.

45 A cover 10 for closing the lower end of the case is fixed to a ring 11 which has a channel 50 12 fitting the end of the case 5. The cover and ring are adapted to be removed by the black powder charge 8 which when ignited serves as an expelling charge.

55 A shade for intercepting the upwardly directed light rays during the descent of the flare is of an

umbrella type and comprises a flexible fire-proofed fabric 13 carried by a plurality of metal ribs 14 and secured thereto by fasteners 15. A band 16, secured to the case by screws 17 which enter a block 5a, is formed with a plurality of spaced and laterally projecting U-shaped extensions 18 each of which carries a transversely mounted bolt 19 for pivotally supporting one of the ribs 14. A spring 20 coiled on the bolt is anchored to the extension and to the rib and normally tends to swing the rib outwardly to an extended position where it is brought to rest by engagement with the extension.

5 The ribs are normally held in folded position parallel to the wall of the case by means of the ring 11. An inexpensive and convenient arrangement for effecting engagement between the ring and ribs consists in the provision of a flange 21 on the ring which is provided with holes 22 for receiving the end of the ribs.

20 When the flare is launched, the shade is in the folded position shown in Fig. 2. When the flare is ignited during its descent, the combustion of the black powder charge 8 expels the cover 10 and ring 11. The ribs being released by removal 25 of the ring are immediately moved to the extended position by the springs 20, this movement being limited by engagement of each rib with the corresponding extension.

I claim:

30 1. In a flare launchable from aircraft, a case, an illuminating composition in the case, a ring fitting on the lower end of the case, a cover fixed to the ring and normally closing the lower end of the case, a powder charge interposed between the cover and illuminating composition and adapted upon ignition to ignite the illuminating composition and blow the cover and ring from the case, a foldable shade pivotally mounted on the outside of the case and held in folded position by engagement with the ring, and means for moving the shade to extended position when disengaged from the ring.

35 2. In a flare launchable from aircraft, a case adapted to house a flare, a channeled ring engaging the lower end of the case between the walls forming said channel, and having an external flange with retaining openings, a cover normally closing the lower end of the case fixed to the ring, common means operable to simultaneously ignite 45 said flare and remove the cover and ring from said case, a band fixed to the case having laterally projecting U-shaped extensions, a pin carried by each extension, a rib pivotally mounted on each pin and having one end normally in- 50

- 5 serted in a retaining opening in the flange of the ring, a spring for each rib adapted to move said rib when disengaged from the flange of the ring to an extended position limited by engagement with its cooperating extension of the band, and a flexible shade carried by the ribs.
3. In a flare launchable from aircraft, a case, a closure on one end of the case, common means operable during descent of the flare for removing 10 the closure and igniting the flare, a band fixed to the case having laterally projecting U-shaped extensions, a pin carried by each extension, a rib pivotally mounted on each pin intermediate the arms of its cooperating extension and having one end normally engaged and held by the closure when in place on the case, a spring encircling each pin and having projections anchored 15 between its cooperating rib and extension tensioned to move said rib when disengaged from the closure to an extended position limited by

engagement with the extension of the band, and a flexible shade carried by the ribs.

4. In a flare launchable from aircraft, a cylindrical case, an illuminating composition in the case, a ring of channel cross-section engaging the lower edge of the case in secured relation, said ring having an outwardly extending flange provided with retaining apertures and an inwardly extending flange, a reflector provided with projecting ribs normally engaged in said retaining 10 apertures hinged to the outside of the case, a cup shaped cover secured to said ring beneath the inwardly extending flange in sealed relation with the inner wall forming said channel ring member and an ignition charge interposed between the illuminating composition and inwardly extending flange adapted upon ignition to simultaneously blow off the cover and ring and ignite the illuminating composition, whereby the reflector may distend to operative position. 15
